CHAIR

Joseph C. Higgins, Chicago, Ill.

Application December 4, 1952, Serial No. 22,551

Term of patent 14 years

(Cl. D15—8)

To all whom it may concern:

Be it known that I, Joseph C. Higgins, a citizen of the United States, residing at Chicago, in the county of Cook and State of Illinois, have invented a new, original, and ornamental Design for a Chair, of which the following is a specification, reference being had to the accompanying drawing, forming part thereof.

In the drawings:

The characteristic features of my design reside in those portions shown in full lines in the drawings.

I claim:

The ornamental design for a chair, substantially as shown and described.

JOSEPH C. HIGGINS.
